(57) **CLAIM**

The ornamental design for a drink data storage device, as shown and described.

DESCRIPTION

FIG. 1 is a front elevation view of a drink data storage device showing my new design.

FIG. 2 is a back side elevation view of the drink data storage device.

FIG. 3 is a right side elevation view of the drink data storage device.

FIG. 4 is a left side elevation view of the drink data storage device.

FIG. 5 is a top plan view of the drink data storage device; and,

FIG. 6 is a bottom plan view of the drink data storage device.
